(57) **CLAIM**

The ornamental design for a cell phone housing, as shown and described.

DESCRIPTION

FIG. 1 is a perspective view of the cell phone housing showing my new design in the closed position.

FIG. 2 is a front view of the cell phone housing showing my new design in the closed position.

FIG. 3 is a back view of the cell phone housing showing my new design in the closed position.

FIG. 4 is a bottom view of the cell phone housing showing my new design in the closed position.

FIG. 5 is a top view of the cell phone housing showing my new design in the closed position.

FIG. 6 is a left side view of the cell phone housing showing my new design in the closed position.

FIG. 7 is a right side view of the cell phone housing showing my new design in the closed position.

FIG. 8 is a perspective view of the cell phone housing showing my new design in the extended position.

FIG. 9 is a front view of the cell phone housing showing my new design in the extended position.

FIG. 10 is a back view of the cell phone housing showing my new design in the extended position.

FIG. 11 is a bottom view of the cell phone housing showing my new design in the extended position.

FIG. 12 is a top view of the cell phone housing showing my new design in the extended position.

FIG. 13 is a left side view of the cell phone housing showing my new design in the extended position; and,

FIG. 14 is a right side view of the cell phone housing showing my new design in the extended position.
